(57) **CLAIM**

We claim, the ornamental design for air conditioner, as shown and described.

DESCRIPTION

FIG. 1 is the front perspective view of air conditioner showing our new design;

FIG. 2 is the front view thereof;

FIG. 3 is the rear view thereof;

FIG. 4 is the side view thereof;

FIG. 5 is the side view thereof;

FIG. 6 is the side plan view thereof; and,

FIG. 7 is the side plan view thereof.

The broken lines in the drawings illustrate portions of the air conditioner which form no part of the claimed design.
